UNITED STATES PATENT OFFICE.

GEORGE E. SKAGGS, OF ST. LOUIS, MISSOURI.

MOTOR.

1,189,399.

Specification of Letters Patent.

Patented July 4, 1916.

Application filed June 10, 1915. Serial No. 33,350.

To all whom it may concern:

Be it known that I, GEORGE E. SKAGGS, a citizen of the United States, residing at St. Louis, Missouri, have invented a certain new and useful Improvement in Motors, of which the following is a full, clear, and exact description, such as will enable others skilled in the art to which it appertains to make and use the same, reference being had to the accompanying drawings, forming part of this specification.

My invention relates to motors of the type wherein an internal combustion engine is combined with a turbine, the principal object of my invention being to provide a comparatively simple apparatus for economically generating power by combustion or explosion of gases or liquid hydrocarbon vapor.

20 In the operation of internal combustion engines such as are now in general use, it will be understood that a comparatively high degree of pressure is developed at the instant the explosion of the gases in the cylinder takes place and I propose to utilize this pressure for the operation of a turbine, and which latter is arranged to drive the piston of the compressor for the gases or hydrocarbon vapor.

25 A further object of my invention is to provide means adjacent to the combustion chamber of the motor for automatically permitting unexploded gases to discharge from said combustion chamber to atmosphere in the event that a charge of combustible gas is drawn into said chamber and for any cause whatever, fails to ignite, thus preventing explosive gases from being delivered into the burnt gas pressure tank.

30 With the foregoing and other objects in view, my invention consists in central novel features of construction and arrangement of parts, hereinafter more fully described, claimed and illustrated in the accompanying drawings, in which—

Figure 1 is a diagrammatic view of a motor of my improved construction with parts thereof in vertical section. Fig. 2 is a sectional view of the cylinder in which the gases are exploded. Fig. 3 is a plan view of the gas explosion cylinder. Fig. 4 is an enlarged sectional view taken approximately on the line 4—4 of Fig. 3.

Referring by numerals to the drawings which illustrate the preferred embodiment of my invention, 10 designates a suitable

turbine, the shaft 11 of which carries a worm 12 which drives a worm wheel 13, the same being mounted on a suitable shaft 14. Fixed on this shaft is a crank 15 to which 60 is connected one end of a pitman 16, the opposite end being connected to a cross head 17 which operates between suitable guides 18.

Arranged a suitable distance away from the turbine is a compression cylinder 19 provided at one end with a head 20 and operating through a stuffing box in the center of said head is a piston rod 21, the outer end of which is connected to cross head 17. Fixed on this rod within cylinder 19 is a 70 piston 22.

Leading through the head 20 to the space within the compression cylinder is a tube 23 in which is located an ordinary check valve 24, it being understood that this tube 75 leads from an ordinary carbureter and which latter is supplied with gas or liquid hydrocarbon from a suitable source of supply.

Located adjacent to cylinder 19 is an explosion cylinder 25, the same being closed at both ends and arranged within said cylinder is a piston 26, the same being carried by piston rod 21 which latter operates through one of the heads of said explosion cylinder. 85

Leading from the chamber within cylinder 19 to the chamber within cylinder 25 is a tube 27 in which is located a check valve 28, the same being arranged to prevent the passage of gases and the pressure thereof from the explosion cylinder 25 to the compression cylinder 19.

Located in the head at the forward end of the explosion cylinder is an ordinary spark plug 30. Leading upwardly from the 95 forward end of cylinder 25 is a vent pipe 31 in which is located a valve housing 32, and leading from one side of said valve housing to a pressure tank 33 is a tube 34 in which is located a check valve 35. 100

Formed through the side of valve housing 32 opposite the point to which pipe 34 connects is an opening 36 and arranged for operation within the valve housing is a cylindrical valve 37, the same being provided 105 with a port 38 which, when the valve is rocked, is adapted to establish communication between the pipes 31 and 34 or between pipe 31 and outlet 36.

Leading from pressure tank 33 to the turbine 10 is a pipe 39 in which is located an ordinary cut-off valve 40.

Fixed to the stem of valve 37 on the outside of valve housing 33 is an arm 41 which is provided with a horizontally disposed slot 42.

5 Formed integral with or fixed to cylinder 25 is an upwardly projecting tubular member 43, and formed in the central portion of the opening therethrough is an annular shoulder 44. The space within this tubular member below this shoulder is slightly smaller than the space above said shoulder and mounted for operation in the lower chamber is a piston 45 which is carried by a piston rod 46, the same operating through 10 a cap 47 which closes the upper end of said tubular member 43.

Loosely mounted on the piston rod 46 within the chamber above shoulder 44 is a piston 48 and interposed between said piston 20 and the cap 47 is a compression spring 49, the same normally maintaining piston 48 on the shoulder 44.

Fixed to the upper end of piston rod 46 is an angle bracket 50 in which is seated a 25 pin 51, the same extending through slot 42 in arm 41 and projecting outwardly from the angle bracket is a pin 52.

Positioned on the upper portion of the rod 46 between cap 47 and angle bracket 30 50 is a compression spring 53, the same being comparatively lighter than the spring 49. Pivotaly mounted on a fixed support 54 directly above the free end of the arm 41 is a spring-held detent 55 provided on its 35 lower end with a hook 56, which latter is adapted to engage beneath the pin 52 when the latter moves upward to its limit of movement with the piston rod 46.

Fixed to the side face of detent 55 near 40 its lower end is an outwardly projecting pin 57. Rigidly fixed to piston rod 21 is the lower end of an upwardly and outwardly curved arm 58, and formed on or fixed to the upper end thereof is a horizontally disposed flange 59, the outer portion of which 45 is inclined as designated by 60 and this flange is adapted to engage on top of pin 52 as the piston rod 21 moves outwardly to carry the piston 26 to the forward end of cylinder 25.

Formed on the upper portion of arm 58 and practically in vertical alinement with the rear end of flange 59 is an upwardly projecting lug 61 which is adapted to engage 55 against pin 57 carried by detent 55 at the time piston rod 21 and parts carried thereby reach the forward limit of their movement.

The operation of my improved motor is 60 as follows: Valve 40 is opened to permit compressed air and burnt gases to pass from storage tank 33 through pipe 39 to turbine 10 and as the latter is operated in the usual manner, shaft 11 carrying worm 12 is rotated, thus driving gear wheel 13 and operating crank 15. Through pitman 18 pis-

ton rod 21 is reciprocated and as piston 22 carried by said rod moves to the lower end of cylinder 19 or away from head 20 a charge of gas or vaporized liquid hydrocarbon will be drawn through pipe 23 into cylinder 19. On the return stroke of piston 22, this charge of gas or vapor will be forced through pipe 27, past check valve 28, into cylinder 25 and by reason of the fact that said cylinder 25 is relatively smaller than the cylinder 19, the charge of gas or vapor will be compressed within said cylinder 25. Pistons 22 and 26 are fixed on piston rod 21 so that they occupy the same relative positions in their respective cylinders, and when piston 22 reaches the forward end of cylinder 19 on the compression stroke, piston 26 will occupy relatively the same position within cylinder 25. When piston 26 reaches the forward end of cylinder 25 or immediately after it begins its movement toward the lower end of said cylinder the timing device in the electric circuit in which spark plug 30 is located closes said circuit to produce spark, and thus the compressed 80 charge within cylinder 25 in front of piston 26 is ignited.

Normally, pistons 45 and 48 occupy the positions as seen in Fig. 2, near the center of the tubular extension 43, and when so positioned, arm 41 is held in a horizontal position with port 38 at a neutral point. The explosion in the cylinder 25 creates for an instant a comparatively high degree of pressure, and this high pressure overcomes the resistance offered by springs 49 and 53 and forces pistons 45 and 48 upward, consequently raising the free end of arm 41 and rocking valve 37 so as to bring port 38 into position to establish communication between pipes 31 and 34. As piston rod 46 is moved upward at the time the explosion takes place, pin 52 will ride past hook 56 and be engaged thereupon, and thus arm 41 and valve 37 are held in their shifted positions. Immediately after the explosion takes place and the valve has been actuated as just described, piston 26 will move to the lower end of cylinder 25 and the burnt gases, which, it will be understood, are compressed to a considerable degree, will find exit through pipe 31, port 38, pipe 34, and past check valve 35 into pressure tank 33.

It will be understood that when the piston rod is moved upward at the time of the explosion in cylinder 25, pin 52 is carried upward out of the path of travel of flange 59. Arm 58 moves forward with piston rod 21 and at a point just prior to the time the piston 26 reaches its forward limit of movement lug or shoulder 61 will strike against pin 57, thereby actuating detent 55 which movement releases pin 52 and under the influence of springs 49 and 53, piston rod and pistons 45 and 48 will move downward to 120 125 130

their normal positions, and consequently returning valve 37 to normal position.

In the event that the charge drawn into cylinder 25 fails to explode, it will be necessary to exhaust said unexploded charge to prevent its entering pressure tank 33, and such exhaust is brought about in the following manner: When a charge fails to explode, the pistons 45 and 48 and piston rod necessarily remain in their normal positions and on the succeeding forward stroke of piston 26, the inclined portion 60 of flange 59 will engage pin 52, thereby moving the same downward, and consequently actuating arm 41 and rocking valve 37 so as to bring port 38 in position to establish communication between pipe 31 and outlet 36. During this movement, piston rod 46 moves freely through piston 48, and such movement only necessitates overcoming the resistance offered by the comparatively light spring 53. During the time pin 52 is positioned beneath the horizontal portion of flange 59, valve 37 is maintained in open condition or to permit the discharge of the unexploded charge from cylinder 25 through pipe 31 and outlet 36 and as pin 50 rides onto the inclined portion 60 of said flange, spring 53 will act to return the piston rod and valve operating arm 41 to their normal positions. Thus, a charge of unexploded gas which would otherwise pass into and mix with the burnt gases in the pressure tank is automatically discharged to atmosphere.

It will be understood that my invention is applicable for a number of compression and explosion cylinders arranged side by side, and it is believed that such arrangement will have a comparatively greater degree of efficiency than where single cylinders are employed.

In some instances it may be found desirable to dispense with the spark plug in the explosion cylinder, and to ignite the explosive charge through high compression as is the practice in the Diesel type of engine.

It will be readily understood that minor changes in the size, form and construction of the various parts of my improved device can be made and substituted for those herein shown and described, without departing from the spirit of my invention, the scope of which is set forth in the appended claims.

I claim:

1. In a motor, the combination with a turbine, of a chamber in which gases are adapted to be ignited, means operated by the turbine for compressing gases within said chamber, a storage chamber adapted to receive the burnt gases from the combustion chamber, means for conveying the burnt gases from the storage chamber to the turbine, a valve in said conveying means, and means for automatically actuating said valve to permit the discharge of unburnt gases

in the event that a charge of gas drawn into the explosion chamber fails to ignite.

2. In a motor, the combination with a turbine, of a chamber in which gases are adapted to be exploded, means operated by the turbine for compressing gases within said explosion chamber, a pressure tank, a connection from the explosion chamber to said pressure tank, a valve in said connection, means adapted to be actuated by the pressure of ignited gases within the explosion chamber for opening said valve to permit the burnt gases from the explosion chamber to pass to the pressure tank, means for automatically actuating said valve to permit the discharge of unburnt gases from the explosion chamber in the event that a charge of combustible gas drawn into said chamber fails to ignite, and a connection from the pressure tank to the turbine.

3. In a motor, a pressure storage tank, a chamber in which gases are adapted to be ignited, a tubular connection from said chamber to the storage tank, a valve located in said tubular connection, means for compressing gases in the chamber, means adapted to be actuated by the pressure from the storage tank for actuating the gas compressing means and means for automatically actuating the valve to permit a discharge of unburnt gases from the combustion chamber in the event that a charge of combustible gas is drawn into said combustion chamber and fails to ignite.

4. In a motor, a pressure storage tank, a chamber in which gases are adapted to be ignited, a tubular connection from said ignition chamber to the pressure storage tank, a gas compressor, means for leading gas from said compressor to the ignition chamber, a turbine adapted to be actuated by pressure from the pressure storage tank, driving connections from said turbine to said gas compressor and means for automatically actuating the valve to permit a discharge of unburnt gases from the combustion chamber in the event that a charge of combustible gas is drawn into said combustion chamber and fails to ignite.

5. In a motor, a turbine, a chamber in which gases are adapted to be exploded, means operated by the turbine for compressing gases within said explosion chamber, a pressure tank, a connection from the explosion chamber to said pressure tank, a valve in said connection, means adapted to be actuated by the pressure of ignited gases within the explosion chamber for opening said valve, means for actuating said valve to open the exhaust port thereof when said valve is not actuated by the pressure of ignited gases within the explosion chamber, and a connection from the pressure tank to the turbine.

6. In a motor, a pressure storage tank, a

- chamber in which gases are adapted to be ignited, a tubular connection from said chamber to the storage tank, a valve located in said tubular connection, means for compressing gases in the chamber, means adapted to be actuated by the pressure from the storage tank for actuating the gas compressing means, means adapted to be actuated by the pressure of ignited gases within 5 the explosion chamber for actuating the valve to permit the burnt gases to pass from the explosion chamber to the pressure storage tank, and means for actuating said valve to permit the discharge of unburnt gases to 10 the atmosphere in the event that a charge 15 of combustible gases drawn into the explosion chamber fails to ignite.
7. In a motor, a chamber in which gases

are adapted to be ignited, a pressure storage tank adapted to receive the burnt gases 20 from said chamber, means actuated by the pressure of the gases from the pressure storage tank for delivering compressed gases to the ignition chamber and means for automatically effecting a discharge of unburnt 25 gases from the ignition chamber in the event that a charge of combustible gas is drawn into said ignition chamber and fails to ignite.

In testimony whereof I hereunto affix my 30 signature in the presence of two witnesses, this 5th day of June, 1915.

GEORGE E. SKAGGS.
